UNITED STATES PATENT OFFICE.

THOMAS W. JOHNSON, OF PHILADELPHIA, PENNSYLVANIA.

APPARATUS FOR REGULATING COMBUSTION IN FURNACES.

No. 838,338.

Specification of Letters Patent.

Patented Dec. 11, 1906.

Application filed January 22, 1906. Serial No. 297,358.

To all whom it may concern:

Be it known that I, THOMAS W. JOHNSON, a citizen of the United States, residing in Philadelphia, Pennsylvania, have invented 5 certain Improvements in Apparatus for Regulating Combustion in Furnaces, of which the following is a specification.

The object of my invention is to so regulate the combustion of fuel in a furnace that 10 such combustion will at all times be effected under uniform or substantially uniform conditions, such conditions being dependent upon gas-pressure in the combustion-chamber exerted against a normally constant 15 counter-pressure and preferably against atmospheric pressure outside of the furnace.

In the accompanying drawings, Figure 1 represents a steam-boiler furnace provided with one form of combustion-regulating apparatus in accordance with my invention, 20 and Fig. 2 illustrates another form of such combustion-regulating apparatus.

Fig. 1 illustrates an ordinary type of boiler-furnace, 1 representing the closed ash-pit; 2, 25 the pipe for supplying to said ash-pit air under pressure for supporting combustion; 3, the combustion-chamber; 4, the stack, and 5 the pivoted damper in said stack, all of these parts being constructed in accordance with 30 the present practice. Mounted at any available point upon a wall of the combustion-chamber is a casing 6, which may be of any desired cross-sectional form and area, the chamber 7 within this casing being in the 35 present instance in communication with the combustion-chamber of the furnace through a neck 6^a, which passes through an opening in the rear wall of said combustion-chamber. Within the chamber 7 is a swinging plate or 40 diaphragm 8, which is pivoted adjacent to one wall of the casing 6, the pivot in the construction shown being adjacent to the top wall of the casing. This diaphragm fits the casing 6 as closely as is compatible with its 45 free swinging movement, and as the casing 6 is open at the outer end the diaphragm is exposed at all times on its outer face to atmospheric pressure and on its inner face to the pressure maintained within the combustion- 50 chamber of the furnace. Hence as the latter pressure varies in respect to the normally fixed atmospheric pressure the diaphragm is caused to swing, and this swinging movement is utilized for the purpose of operating the mechanism for controlling the air-

supply or draft of the furnace, or both. Many forms of mechanism may be utilized for this purpose. Hence it should be understood that the mechanism which I have shown in the present instance is only for purposes of illustration and does not constitute an essential part of my invention. Projecting from the pivot-spindle 9 of the diaphragm 8 is an arm 10, which operates the stem 12 of a valve 13 for controlling the flow 60 of water or other fluid under pressure to the lower portion of a damper-operating cylinder 14, the latter having a piston 15, with weighted rod 16, which is connected by a cord 17, passing over a guide-pulley 18, to a 65 weighted lever 19 on the pivot-spindle of the stack-damper 5. Hence when the piston 15 rises in the cylinder 14 said damper is moved in one direction, and when the piston descends in the cylinder 14 the damper is 70 moved in the opposite direction, free flow of air into or from the upper portion of the cylinder being permitted. Flow of fluid to or from the lower end of the cylinder 14 therefore controls the movement of the piston 80 therein and the consequent operation of the damper, the cutting off of such flow serving to lock the damper in the position to which it had previously been adjusted. The casing of the valve 13 has a fluid-inlet 20, a fluid-outlet 21, and a pipe 22, leading to the cylinder 14, and the valve-stem 12 has two disks 23 and 24, the former constituting the governing element of the valve and the disk 24 being a pressure-equalizing disk. 85

When the disk 23 is in the position shown in Fig. 1, it closes the inlet end of the pipe 22, and hence locks the damper in the position previously assumed by it, movement of the disk 23 in the direction of the arrow *x* permitting flow of fluid under pressure from the inlet-pipe 20 into the pipe 22, and therefore to the cylinder 14, so as to raise the piston in the latter, while movement of the disk 23 in the direction of the arrow *y* from the position shown in Fig. 1 opens the connection between the pipe 22 and the outlet-pipe 21 and permits discharge of fluid from the cylinder 14 and descent of the piston therein. 95

The parts are so arranged that when the pressure in the combustion-chamber is less than atmospheric pressure the diaphragm 8, swinging inwardly under such atmospheric pressure, will cause such an operation of the parts as will impart closing movement 100 of the valve 13. 110

to the damper 5, thereby checking the draft until the pressure within the combustion-chamber again equals or approaches atmospheric pressure and the diaphragm 8 returns to its vertical and normal position. When, on the other hand, the pressure within the combustion-chamber 3 is greater than atmospheric pressure, the diaphragm 8 will swing outwardly, and this will result in an opening of the damper 5, thereby providing a freer outflow from the combustion-chamber and lowering the pressure therein until it again equals or approaches atmospheric pressure and causes the diaphragm to again assume its vertical and normal position.

It has been found in practice that the diaphragm 8 is so sensitive in its action that it is affected by slight changes of pressure in the combustion-chamber, and a condition corresponding closely to atmospheric pressure is constantly maintained in said combustion-chamber, substantially uniform combustion being maintained at all times irrespective of variations in the depth or other conditions of the fuel-bed or in the pressure of the blast, the result being that when the furnace-door is open there will, on the one hand, be no inflow of cold air to the combustion-chamber and, on the other hand, no outward blast of hot gases therefrom.

In Fig. 2 I have illustrated my invention in connection with an electromagnetic controlling device, the arm 10^a of the swinging damper in this case terminating in a switch-finger 10^b, which vibrates between the opposite terminals 25 and 26 of an electric circuit containing two electromagnets 27 and 28, provided with a solenoid-core 29, the latter having a cross-head 30, whose opposite ends are contained between collars 31 on rods 32, suitably guided on opposite sides of the magnets and normally maintained in mid-position by means of upper and lower coiled springs 33, interposed between the collars 31 and the fixed guides 34 for the rods 32. The lower ends of the rods 32 carry a cross-head 35, which is connected to the stem 36 of a valve 37, the latter having an inlet 38 for water or other fluid under pressure, two outlets 39 and 40 communicating, respectively, with the upper and lower ends of a damper-operating cylinder 14^a, and a discharge-outlet 41, communicating directly with one end of the valve-chest 37 and through a pipe 42 with the opposite end of the same. The valve-stem 36 has two disks 43 and 44, which normally close the outlets 39 and 40 and cut off communication between the cylinder 14^a and the inlet-port 38 or discharge-port 41 of the valve-chest.

When the swinging diaphragm 8 occupies its normal or vertical position, the switch-finger 10^b is free from contact with either of the terminals 25 and 26. Hence neither of the electromagnets 27 or 28 is energized, and

the solenoid-core 29 occupies a mid-position corresponding with the normal or like position of the valve-disks 43 and 44. When, however, the diaphragm 8 swings outwardly, the switch-finger 10^b is caused to contact with the terminal 25, the upper magnet 27 is energized, the solenoid-core is raised, and corresponding movement is imparted to the valve-stem 36, thereby opening the upper end of the cylinder 14^a to the fluid-inlet 38 and the lower end of said cylinder to the fluid-outlet 41 and causing a descent of the piston 15^a in the cylinder and a movement of the stack-damper to increase the draft of the stack. When, on the other hand, the diaphragm 8 swings inwardly, the switch-finger 10^b is moved so as to contact with the terminal 26, the lower magnet 28 is energized, the solenoid-core 29 is depressed, and there is a like movement of the valve-stem 36, so as to open communication between the lower end of the cylinder 14^a and the fluid-inlet 38 and between the upper end of said cylinder and the outlet 41, thus causing a rise of the piston 15^a in the cylinder and a movement of the damper 5 to check the draft in the stack.

While I prefer in all cases to use the swinging diaphragm 8 because of the sensitiveness of the same, it will be evident that a flexible diaphragm or a sliding piston might be used in place of the same, any of these devices being intended to be covered by the term "primary member" as used in my claims, unless the swinging diaphragm is specifically referred to therein, and instead of controlling the movement of the stack-damper alone the movements of said primary member may be caused to control a damper in the pipe 2, which supplies the air-blast to the closed ash-pit of the furnace, such a damper being illustrated at 46 in Fig. 2, or the movement of the primary member 8 may be transmitted both to the stack-damper and to a valve in the steam-pipe which supplies the blast-fan-driving engine, such a valve being illustrated at 47 in Fig. 1, or either the blast-pipe damper or the engine-regulating valve may be used in connection with an open stack or with a stack having a normally fixed damper, or my invention may be employed for regulating either the air-supply or stack-draft, or both, in a furnace having natural draft instead of forced draft, what I consider to be the essentially novel feature of my invention being the utilization of varying pressures within the combustion-chamber of the furnace for effecting control of the combustion.

Any normally fixed pressure, such as that of a weight or a body of water or other fluid acting against the primary element of the regulating apparatus, may be employed in place of atmospheric pressure as the agent opposed to the combustion-chamber pressure; but atmospheric pressure is preferred, as it dispenses with all means for preventing

leakage and permits the use of the swinging diaphragm or other freely-moving body as the primary element.

No attempt has been made to show in the drawings the relative proportions of the parts, as this would necessitate too small a scale for some of them.

I claim—

1. Combustion-regulating apparatus for furnaces having as elements a regulating device actuated by fluid under pressure, a valve governing the operation of said device, and a swinging plate supported so as to tend to remain in a neutral position under the action of gravity and placed to govern the movement of said valve, said plate being acted upon in one direction by a normally fixed pressure and in the other direction by the pressure in the combustion-chamber.
2. Combustion-regulating apparatus for furnaces having as elements a regulating device actuated by fluid under pressure, a balanced valve governing the operation of the same, and a swinging plate connected to said valve and supported so as to tend to maintain the valve in its closed position under the action of gravity, said plate being acted upon

in one direction by atmospheric pressure and in the other direction by the pressure in the combustion-chamber.

3. Combustion-regulating apparatus for furnaces having as elements a regulating device actuated by fluid under pressure, a valve governing the operation of said device, a swinging plate supported so as to tend to remain in a neutral position under the action of gravity, and provided with a pair of contacts, a movable member connected to the plate and coacting with said contacts, and electrical apparatus connected to the valve so as to govern the operation of the same and included in the circuit with said contacts, the plate being placed to be acted on in one direction by a normally constant pressure and in the other direction by the pressure in the combustion-chamber.

In testimony whereof I have signed my name to this specification in the presence of two subscribing witnesses.

THOS. W. JOHNSON.
